United States Patent Office

Des. 204,403

Patented Apr. 12, 1966

204,403

CHRISTMAS TREE HOLDER

Walter Goodridge, North Providence, R.I., assignor to Flowerized Presentations, Inc., North Providence, R.I., a corporation of New York

Filed May 27, 1965, Ser. No. 85,485

Term of patent 14 years

(Cl. D35—3)

FIG. 1

FIG. 3

FIG. 1 is a view in perspective of my Christmas tree holder;

FIG. 2 is a view in side elevation; and

FIG. 3 is a bottom plan view.

The broken line, fragmentary showing of the tree member in FIG. 1 is shown for illustrative purposes only.

I claim:

The ornamental design for a Christmas tree holder, as shown and described.
